US00D904190S

(12) **United States Design Patent** (10) Patent No.: **US D904,190 S**
(45) Date of Patent: ** Dec. 8, 2020

(54) **CONTAINER**

- (71) Applicant: **PepsiCo, Inc.**, Purchase, NY (US)
(72) Inventors: **Advait Bhat**, White Plains, NY (US);
Girish Nilkanth Deshpande, Carmel, NY (US); **Maximiliano Rodriguez**, Bridgewater, NJ (US); **Benjamin Joseph Tantanella**, New York, NY (US); **Bruno Telesca**, Sandy Hook, CT (US); **Alexander David Warning**, Peekskill, NY (US); **Lei Zhao**, Nanuet, NY (US); **Nathan Daniel Grubbs**, West Chester, OH (US); **Ryan Alan Klenke**, St. Henry, OH (US)
(73) Assignee: **PepsiCo, Inc.**, Purchase, NY (US)
(**) Term: **15 Years**
(21) Appl. No.: **29/737,125**
(22) Filed: **Jun. 5, 2020**

Related U.S. Application Data

- (63) Continuation of application No. 29/675,128, filed on Dec. 28, 2018, now Pat. No. Des. 887,272.

(57) **CLAIM**

The ornamental design for a container, as shown and described.

DESCRIPTION

FIG. 1 is a top front perspective view of a container showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the container that form no part of the claimed design.

1 Claim, 8 Drawing Sheets
